EXHAUST MANIFOLD DEVICE

Charles R. Flint, La Porte, Ind.

Application April 29, 1947, Serial No. 744,582

13 Claims. (Cl. 60—30)

1
This invention relates to a vacuum accumulator, and more particularly to a vacuum accumulator intended for application to an exhaust manifold of an internal combustion engine.

It is well known that following the explosion of a charge in a cylinder of an internal combustion engine of the 4-cycle type and the opening of the exhaust valve, the compressed burnt gases tend to evacuate the cylinder as a mass leaving in their wake a void within the cylinder. In the ordinary type of internal combustion engine, the void is partially replaced by exhaust gases returning to the cylinder. The succeeding charge, when drawn into the cylinder, then becomes partially mixed with burnt gases from the preceding explosion with the resulting lessening in the efficiency of the engine.

I have invented, and am herein disclosing and claiming a vacuum accumulator adapted to be attached to the exhaust manifold of an internal combustion engine which in its operation supplies fresh air via the exhaust manifold to the cylinder immediately after the evacuation of the burnt gases therefrom. Inasmuch as fresh air is introduced to the cylinders in place of returned burnt gases as in previous constructions, the efficiency of the engine is greatly increased with a resulting saving in power and fuel.

The present device includes two valves, which have been found to prevent clouding of the device with moisture due to escape of some exhaust gas past a single check valve while it is still open.

The device has also been found to produce a fog of condensed moisture during times of decompression within the tube, and this phenomenon is particularly associated with the stepped portions of the tubing, where the expansion occurs. It is obvious that to increase this function without producing clogging of the tube with moisture, the device should be mounted in a relatively cool position in the engine, and the tube itself should be relatively unencumbered to provide a steady escape of gases through it.

It has been found in actual operation of the device in automobiles, that the exhaust valves of cylinders connected to the exhaust manifold are maintained remarkably clean. This appears to be a function of the condensed moisture produced within the tube or accumulated, which is carried within the cylinders during fluctuations of pressure within the system.

This application is a continuation-in-part of my copending applications Serial No. 559,824, filed October 21, 1944, now Patent No. 2,482,750, and

2
Serial No. 718,721, filed December 27, 1946, now abandoned.

The condensation of moisture is increased if the tube used is not connected with the atmosphere, but the device does not then have some of its other advantages.

The invention will be described as embodied in the accompanying drawing in which

Fig. 1 is a side elevation of the device, and **Fig. 2** is a vertical cross section, partly broken away, of the device shown in **Fig. 1**.

The vacuum accumulator comprises an open-ended booster tube **10** adapted at one end to be connected to the exhaust manifold of an internal combustion engine **10a** and having the other end **11** of the tube opening to a housing chamber **12**. The housing chamber is shown as comprising four parts, the end **13**, the union **14**, the chamber housing **15** and the end closure **16**. It will be noted that the housing forms a housing chamber **17** about the tube **10** which chamber is not greatly larger than the tube. For example, with a tube $1\frac{1}{2}$ " in internal diameter, the entire housing chamber is suitably not much more than $\frac{1}{2}$ " in diameter. The tube **10** terminates slightly short of the end **16** of the housing. The tube **10** is about 12 inches long and the effective length of the chamber **17** about 7 inches and the tube **18** about 9 inches.

The division shown for the housing is preferred for ease of assembly. It is obvious that the entire device may be made in one piece, if desired.

Communicating with the housing chamber is an air reservoir, generally designated as **18** which has a threaded end **19** threading into the union **14**, a right angular curved portion **20**, a reservoir portion **21**, and an air filter **22**. The reservoir portion **21** is defined between the check valves **23** and **24**.

40 Each check valve comprises an annular valve seat **25** against which a neoprene diaphragm **26** and a metal diaphragm **27** are pressed by a very light leaf spring **28**. The diaphragm has a larger diameter than the valve seat **25** so that its edges project thereover into the space **29**. The check valves are so arranged that air is permitted to flow in one direction only through opening **30**, that is in a direction from the air filter towards the housing chamber **17**. The diaphragms are lightly constructed so as to have substantially no inertia. The air filter **22** is of usual construction, comprising a cover **31**, a housing **32**, an air cleaner screen **33** enclosing a filter material **34**.

Also communicating with the housing is a surge

chamber 39 communicating with the housing chamber through an opening 36 which is partially closed by a diaphragm 37 having an opening 38 therein. The chamber is closed by a plug 49. The surge chamber serves as an additional vacuum accumulator.

A clamp 41 serves to hold the air reservoir 18 against excessive vibration.

The figures in the drawing are drawn to scale, the size being of considerable importance, although the spacing and size may vary in accordance with the particular motor with which the device is associated.

Having described the structure of my invention, its operation will now be explained. The exploded gases within the cylinder of an internal combustion engine are under pressure. The opening of the exhaust valve initiates the hereinabove mentioned effect in the gases will thereupon tend to evacuate the cylinder as a mass, leaving a void in their wake. The mass of compressed gases, upon entering the exhaust manifold of the engine, momentarily increase the pressure within the manifold and hence compress the air within the tube 10 and the chamber 17 which are connected to the exhaust manifold. Upon the passing of the compression wave of exhaust gases, a resulting lower pressure area is left in their wake. The tube 10 and the chamber 17 are exposed to this area of reduced pressure and the air therefore is subjected to the same physical laws, and will tend to evacuate the tube and chamber as a mass and rush into the manifold and thence into the cylinder recently evacuated by the exhaust gases. In my said previous constructions, the void left behind in the tube and housing chamber tended to draw the air back into the tube and hence decrease the amount of air remaining within the cylinder. The present invention overcomes this tendency by the provision of the air reservoir 18. Air evacuating the tube and chamber creates an area of lesser pressure within the tube and chamber which causes the valve 23 to open. The air within the reservoir portion 21 is then subjected to the same physical laws. It has been opened to an area of lesser pressure. The air within the reservoir portion thereupon rushes into the housing chamber and tube replacing a portion of the air recently evacuated therefrom, increasing the pressure therein and greatly reducing the tendency of air to return to the tube. The decrease of the pressure within the reservoir portion 21 opens the valve 24 and the reservoir, tube and chamber are recharged by air from the atmosphere in readiness for the next cycle.

The presence of two valves 28 and 24 is of particular value in preventing noisiness of the system. The single valve 28 would permit, under some conditions, direct passage of air under conditions which would produce noise.

The air filter is provided to screen foreign particles from the vacuum accumulator to prevent damage to the valves or to the engine itself. The drawing herein is substantially to scale.

While I have shown and described my invention in its preferred embodiment, it is to be understood that it is capable of many modifications. Changes, therefore, in the construction and arrangement may be made without departing from the spirit and scope of the invention as disclosed in the appended claims.

I claim:

1. A vacuum accumulator comprising: an elongated open-ended tube at least ten times as long

as its diameter, said tube being adapted to be connected to the exhaust manifold of an internal combustion engine, a housing chamber about the tube, an opening from the tube to the chamber, an air reservoir connected to the chamber, said reservoir having an opening to said chamber and an opening to the atmosphere, and means associated with said reservoir permitting a flow of air therein in a direction toward said chamber only.

2. A vacuum accumulator comprising: an elongated open-ended tube at least ten times as long as its diameter, a housing chamber about the tube, said tube being adapted to be connected at one end to the exhaust manifold of an internal combustion engine and opening at the other end to the chamber, an air reservoir communicating with the chamber and with the atmosphere and means within said reservoir permitting a flow of air therein in a direction toward said chamber only.

3. The vacuum accumulator of claim 2 in which said flow permitting means comprises a first valve adjacent the opening of the reservoir into the chamber and a second valve adjacent the opening of the reservoir to the atmosphere.

4. The vacuum accumulator of claim 2 in which said reservoir is a pipe being at least ten times as long as its diameter.

5. A vacuum accumulator comprising: an elongated open-ended tube at least ten times as long as its diameter, a housing chamber about the tube, said tube being adapted to be connected at one end thereof to the exhaust manifold of an internal combustion engine and the other end of said tube opening to said chamber, an air reservoir comprising a pipe at least ten times as long as its diameter opening at one end thereof to said chamber and opening to the atmosphere at the other end, a first check valve having a diaphragm of no substantial inertia within said pipe adjacent the chamber end thereof, and a second check valve having a diaphragm of no substantial inertia adjacent the other end of said pipe.

6. The vacuum accumulator of claim 5 including a blow-out plug communicating with said chamber.

7. The vacuum accumulator of claim 5 including an air filter mounted on the pipe adjacent the other end thereof.

8. The vacuum accumulator of claim 5 in which the housing chamber extends substantially the entire length of the tube.

9. In an internal combustion engine having a plurality of cylinders operatively connected to an exhaust manifold, a vacuum accumulator, comprising: an elongated open-ended tube at least ten times as long as its diameter, one end of said tube being connected to the exhaust manifold, a housing chamber about the other end of the tube, a pipe at least ten times as long as its diameter opening to said chamber at one end and opening to the atmosphere at the other end, a first check valve having a diaphragm of no substantial inertia within said pipe adjacent the chamber end thereof, and a second check valve having a diaphragm of no substantial inertia adjacent the atmosphere end of said pipe, said pipe and check valves being adapted to admit air through said tube to the exhaust manifold during operation of the engine.

10. An accumulator as set forth in claim 1 including a surge chamber attached to the housing chamber and opening thereto through a restricted opening.

11. In an engine of a four cycle type having a plurality of cylinders communicating with an exhaust manifold through exhaust valves, a vacuum accumulator, including: an elongated open-ended tube connected at one end to said exhaust manifold, said tube being at least ten times as long as its greatest diameter, an air reservoir pipe communicating with the other end of said tube, said tube being exposed to intermittent increases in pressure within said manifold during operation of the engine to cause compression of the air within the tube, expansion of the air so compressed producing a fog of condensed moisture.

12. In an engine as set forth in claim 11 the further feature that said pipe is closed at its remote end by an inwardly opening check valve of no substantial inertia.

13. In an engine as set forth in claim 11 the further feature that said pipe is closed at its remote end by an inwardly opening check valve of no substantial inertia and in which an intermediate inwardly opening check valve of no substantial inertia is likewise provided within the pipe.
